UNITED STATES PATENT OFFICE.

GEORGE DORFFEL, OF WEST SEATTLE, WASHINGTON.

LIFEBOAT.

1,351,627.

Specification of Letters Patent. Patented Aug. 31, 1920.

Original application filed May 14, 1919, Serial No. 297,015. Divided and this application filed September 10, 1919. Serial No. 322,773.

To all whom it may concern:

Be it known that I, GEORGE DORFFEL, a citizen of the United States, and a resident of West Seattle, in the county of King and State of Washington, have invented new and Improved Lifeboats, of which the following is a full, clear, and exact description.

This invention relates to life boats, and has reference more particularly to life boats or escape buoys for use with submarine vessels. The invention also relates to a submarine vessel having a life boat associated therewith, and so arranged that it can be readily released in case of emergency and is itself preferably capable of submarine operation.

The object of the invention is to provide a life boat or escape buoy for submarine vessels, which can be easily and quickly launched, which is carried in position by the submarine vessel, so that interior access thereto can be had at all times before launching, the launching and operation of which will not readily be interfered with by stress of weather, and which will not unfavorably affect the normal operation or maneuvering of the submarine vessel.

The invention consists in the construction and combination of parts to be more fully described hereinafter and particularly set forth in the claims.

Reference is to be had to the accompanying drawings forming a part of this specification, in which similar characters of reference indicate corresponding parts in all the views, and in which

Figure 1 is a longitudinal section of a life boat of my invention, showing the same mounted in a crib or carrier of the main submarine;

Fig. 2 is a plan view of the life boat and its crib or carrier;

Fig. 3 is a partial, transverse section, showing certain of the details of construction of the life boat;

Fig. 4 is an enlarged, transverse section on the line 4—4 of Fig. 1; and

Fig. 5 is an enlarged, fragmentary, side elevation of a detail of construction.

One of the disadvantages incident to the operation of submarines, both for military and mercantile purposes, is found in the difficulty of providing suitable life-saving equipment for the submarine, which will

not interfere with the normal operation or maneuvering of the submarine, and will not materially reduce its speed. Furthermore, in providing such life boats or escape buoys it has been found difficult to have them accessible at all times to the crew of the submarine, and to carry them in such a way that they can be readily launched regardless of weather conditions. One of the primary purposes of my invention is to provide a life boat to insure the safe escape of the crew of the submarine, in case of accident. It will be understood that this type of life boat can be employed with submarines of all kinds, and is not restricted for its utility to any particular type. Many of the details of construction shown herewith for example, form no part of my invention and may be varied as desirable or necessary.

The present application is a division of my application Serial No. 297,015, filed May 14, 1919, for submarine vessels.

My life boat E is preferably in the form of a small, auxiliary submarine in general type similar to the submarine C of my application Serial No. 297,015, above mentioned. However, while completely closed, it is not necessarily provided with diving mechanism and controls. It is provided with hatches 89 having hatch covers 90 and cover-securing means 91. It also has propelling mechanism 92, similar to that of the said submarine C, and connected with a propeller 93, and is provided with the usual rudder 94 operated from a steering wheel 95. It also has an air pump 96 and air pipes 97 by means of which the air can be renewed when necessary. It is likewise provided with a periscope 98 and has the usual compartments 99 and 100.

In order to afford communication between the mother submarine and the lifeboat, the wall of the former has an opening 101 surrounded by an offset coaming 102. A tapered, hollow member 103 extends from an opening 104 in the wall of the lifeboat, through the opening 101, it being provided with a lateral flange 105 seating against the wall of the lifeboat about the opening 104. An annular, tapered frame 106, having a lateral flange 107, fits into the opening 104, with its flange seating against the inside of the wall of the life boat. It has a hinged cover 108 adapted to seat against the flange 107 and to close the open-

ing. A suitable hook 109 is provided to hold the hinged cover in an open position. I provide a cover plate 110 slidably mounted in offset guides 111 carried by the 5 coaming 102. The cover plate 110 is adapted to seat against the inner rim of the member 103, to close the opening. A yoke 112 is mounted upon the coaming, extending over the cover plate, and has a centrally positioned bolt 113, adapted to engage the cover plate and to secure it in position.

The life boat carrier consists of a substantially rectangular frame of suitable plate metal, having a top 114, a bottom 115, 15 ends 116 inclined outwardly from the wall of the mother submarine, and forming a substantially rectangular opening into which the life boat fits, and in which it rests securely. These parts are respectively inclined with respect to the side of the vessel and are arranged to offer a minimum resistance to its passage through the water. The edge of the bottom 115 has an inturned flange 117 to afford a seat of suitable surface for the bottom of the life boat. To 20 strengthen the carrier, braces 118 are secured between the wall of the mother submarine and the top, bottom and ends of the carrier.

The life boat is secured in place in the carrier, by means of a plurality of chains 119, 30 shown for example as eight in number. Each of these chains has one extremity secured to an eye-bolt 120 passing through a suitable sleeve 121 in the wall of the mother submarine. A bracket 122 extends over each of the sleeves 121 and has an opening to receive the threaded end of the eye-bolt. Holding and adjusting nuts 123 on the threaded end of the eye-bolt engage the bracket. By means of these bolts the chains 40 can be tightened and adjusted when necessary. The chains are arranged in pairs, one passing over the top of the life boat and the other under the bottom. The life boat for each such pair of chains is provided with a drum 124 passing through an opening in the outer side wall and positioned in bearings 125 and 126 which are mounted in a sleeve 127 disposed in the opening in the wall. A 45 collar 128 is secured to the inside of the life boat and encompasses the sleeve, having a flange 129 which fits closely about the sleeve. At the outer or projecting end, the drum has a pair of hooks 130 each adapted to engage 50 a link of the chain, as is shown in Fig. 12. It will readily be understood that by turning the drum, the chains can be wound thereupon to tighten them. Conversely, when it is desired to release the life boat, 55 the drums need merely be turned until the hooks disengage from the chains, and the boat is free to slide from the carrier. At the inner end, each drum has a head 131 provided with peripheral sockets 132 in which 60 can be inserted an operating bar or lever to

facilitate the turning of the drum. The latter also has adjacent to the head 131, a ratchet 133 with which co-operates a pawl 134, so that the drum can be held in any adjusted position. The pawl 134 is mounted 70 on a stud 135 carried by a bracket arm 136.

Having thus described my invention, I claim as new, and desire to secure by Letters Patent:—

1. In combination, a submarine vessel, a 75 life boat carrier mounted thereon, a life boat seated in said carrier, and flexible means exteriorly of the submarine and of the life boat for securing said life boat in position, said means being adjustable from within 80 said submarine vessel and being releasable from within said life boat.

2. In combination, a submarine vessel, a life boat carrier mounted exteriorly thereon, 85 a life boat supported in said carrier, a chain secured at one end to and extending from said vessel for securing at its free end, said life boat in position, means operable from within said submarine vessel for adjusting the tension of said chain, and means operable from within said life boat for releasing the free end of said chain from the life boat. 90

3. In combination, a submarine vessel having a life boat carrier at one side thereof, a life boat seated in said carrier, a chain for 95 holding said life boat in position, means for securing one end of said chain to said submarine vessel, and a drum extending from within said life boat and having means exteriorly of the lifeboat for engagement with 100 said chain.

4. In combination, a submarine vessel having a life boat carrier at the side thereof and entirely outside, a life boat seated in said carrier, chains for holding said life boat in 105 position in said carrier, means for securing one end of said chains to said submarine vessel, said chains adapted to pass over the top and bottom and one side of the lifeboat, a drum extending laterally from within said lifeboat and having means for engagement with the free ends of said chains, means within said lifeboat for operating said drum to secure or release said chains, and means for holding said drum in different adjusted 110 positions.

5. In combination, a submarine vessel having a lifeboat carrier at one side thereof and entirely outside the said vessel, said carrier comprising a sloping top, end and bottom walls, said walls converging from the sides of the submarine vessel to form an opening to receive a lifeboat, a lifeboat in said opening, the bottom wall having a transversely extending flange constituting a seat and support for said lifeboat, and means for removably securing the said lifeboat in said carrier. 115 120 125
